(57) CLAIM

The ornamental design for a set of radiation breast shields for everyday use, as shown and described.

DESCRIPTION

FIG. 1 is a perspective view of a set of radiation breast shields for everyday use showing my new design on a phantom torso;

FIG. 2 is a bottom view of one of the breast shields of the set shown flat;

FIG. 3 is a top view of FIG. 2;

FIG. 4 is a bottom view of the other breast shield of the set shown flat; and,

FIG. 5 is a top view of FIG. 4.

The broken lines showing a person wearing a brassiere in FIG. 1 are for illustrative purposes only and do not form part of the claimed design. The broken lines shown on the radiation breast shields in FIGS. 2 and 4 represent stitching that is part of the claimed design.
